UNITED STATES PATENT OFFICE.

HERMANN JAWORSKI, OF NEW HAVEN, CONNECTICUT, ASSIGNOR TO
SARGENT & CO., OF SAME PLACE.

DESIGN FOR A BRACKET.

SPECIFICATION forming part of Design No. 12,244, dated May 3, 1881.

Application filed March 28, 1881. Term of patent 14 years.

To all whom it may concern:

Be it known that I, HERMANN JAWORSKI, of New Haven, in the county of New Haven and State of Connecticut, have invented a new Design for Brackets; and I do hereby declare the following, when taken in connection with the accompanying drawing and the letters of reference marked thereon, to be a full, clear, and exact description of the same, and which said drawing constitutes part of this specification, and represents in the figure a side view.

This invention relates to a design for cast-metal brackets such as used for supporting shelves and like purposes; and the invention consists in the configuration of the bracket, as hereinafter described, and shown in the accompanying illustration.

A represents the back, and B the arm extending at right angles therefrom in the usual manner. Parallel with the back A is a vertical bar, C, and that bar, turning at right angles, forms a corresponding bar, D, parallel

with the arm B. The bars C D stand a little distance from the back and arm, but connected thereto at intervals, as at a, showing a series of open spaces between the back and arm and the respective bars. A quadrant-shaped brace, E, extends from the bar C up to the bar D, the brace made open with a branch, F, extending therefrom to the bar C, and a similar branch, G, to the bar D. The branches F G may be omitted.

I claim—

The design for bracket, consisting of the bars C D, parallel, respectively, to the back and arm, and connected to each with a quadrant-shaped brace, E, extending from the bar C to the bar D, as shown in the accompanying illustration.

HERMANN JAWORSKI.
